ELECTRICAL SWITCH MECHANISM

Frederick James Pavitt, Brighton, England, assignor to Allen West and Company Limited, Brighton, England, a British company

Application March 8, 1950, Serial No. 148,317
In Great Britain February 28, 1949

13 Claims. (Cl. 209—106)

1

This invention relates to electrical switch mechanism and has for its object to provide an improved electrical switch mechanism of the kind which can be closed manually, tripped with a snap action manually, and tripped with a snap action under faulty electric conditions independently of any manual operation.

The invention consists broadly of an electrical switch mechanism comprising a movable switch element movable in one direction to the closed position of the switch and in the other direction to the open position of the switch and biased to the open position of said switch, an actuating element movable to an operative position and returnable to a non-operative position, a lever pivotably mounted between its ends on said actuating element, a tripping element which is positioned according to the electrical conditions in the circuit controlled by said switch, said tripping element having a normal position which it occupies when said circuit conditions are normal and a tripping position which it occupies when said circuit conditions are abnormal, the arrangement being such that, when said actuating element is moved to the operative position, said tripping element, being at the normal position, retains one end of said lever whereby the other end moves and engages said switch element and conveys it to the closed position of the switch, and, upon said tripping element moving to the tripping position, it releases the first-named end of said lever, whereupon said switch element is free to return to the open position of the switch thereby rotating the lever about its pivot.

In order that the invention may be the more clearly understood a switch mechanism in accordance therewith will now be described, reference being made to the accompanying drawings wherein:

Figure 1 is a front elevation of said mechanism;

Figure 2 is a rear elevation of the same;

Figure 3 is a front elevation of the same with some of the front portion of the structure removed, with the switch at the normal open position;

Figure 4 is a similar view to Figure 3 but with the switch at the closed position;

Figure 5 is a cross section of the structure taken on the line V—V of Figure 6;

Figure 6 is a plan of the structure shown partly in section on the line VI—VI of Figure 5;

Figure 7 is a plan of the structure shown

2

partly in section approximately on the line VII—VII of Figure 3;

Figure 8 is a fragmentary view showing certain of the parts when at the tripped position.

Referring to the drawings the switch is a three phase switch comprising three pairs of fixed contacts 1 and three bridging contacts 2. The bridging contacts 2 are mounted in spaced relation along a contact-carrying bar 3 each bridging contact being transverse to the bar and projecting on each side thereof. Said bar 3 is longitudinally slidable to and from a closed position at which the ends of each bridging contact 2 engage its respective pair of fixed contacts 1 and an open position (illustrated in Figure 2) at which each bridging contact disengages its respective pair of fixed contacts. For the sake of clarity of description it will be assumed that the contact-carrying bar 3 is horizontal (as shown in the drawings) and that the bridging contacts 2 are vertical. The contact-carrying bar 3 is spring biased to the open position.

The switch has three windings 4 respectively in circuit with the three phases. These windings 4 have their axes vertical and in a row parallel to the contact-carrying bar 3. Above these windings is a trip plate 5 and said trip plate has an arm 6 extending more-or-less horizontally from one edge thereof. Said trip plate is pivoted at its opposite edge at 7 so that said arm 6 can move up and down, and means are provided, which will be hereinafter described, whereby so long as the windings 4 are energised but not overloaded said trip plate 5 has its arm 6 down, but if an overload or voltage failure occurs in any winding said trip plate is raised to the up position of said arm 6. Means are provided, however, which will be hereinafter described, whereby normally when the switch is not in use said trip plate 5 remains with its arm 6 at the down position.

A start plate 8 is provided in a vertical plane parallel to the contact-carrying bar 3, and said start plate is horizontally slidable in its own plane. Said start plate 8 is spring biased in the same direction as said horizontal bar 3, i.e. to the right according to Figures 3 and 4.

A lever 9 is mounted on said start plate 8 so as to pivot about a horizontal axis 10 transverse to said start plate. Said lever 9 comprises a long arm extending upwardly from its pivot axis 10 and said long arm at its upper end 9a is normally just to the right (according to Fig-

ures 3 and 4) of the aforesaid arm 6 of the trip plate 5. Said lever 9 also comprises a short arm extending to the right from its pivot axis, and said short arm terminates in a downwardly extending hook portion 9b.

To close the switch, the start plate 8 is pushed to the left (according to Figures 3 and 4) in opposition to its spring bias. The upper end 9a of the lever 9 is retained by its engagement with the arm 6 of the trip plate 5, but the lower end of said lever 9 is carried to the left with the start plate 8. When the start plate 8 has reached a given point in its travel to the left, the hook portion 9b of the lever 9 engages a horizontal lateral projection 3a from the contact-carrying bar 3, and thereafter said contact-carrying bar is carried to the left with said start plate. When the bridging contacts 2 have reached the closed position, said start plate 8 is latched against return.

The switch is now closed and the position is as in Figure 4. The long arm of the lever 9 is inclined to the right, and the short arm with the hook portion 9b is inclined downwardly. If overload or voltage failure takes place, the arm 6 of the trip plate 5 will be lifted, and will rise clear of the upper end 9a of the long arm of the lever 9. This leaves said long arm free to move to the left, and accordingly the short arm with the hook 9b to move to the right and upwards. Under the influence of the bias on the contact-carrying arm 3 this movement of the lever 9 takes place until the hook portion 9b is clear of the lateral projection 3a on the contact-carrying bar 3, whereafter said contact-carrying bar springs freely to the fully open position of the switch. The lever 9 is now at a limiting position with its long arm inclined to the left and its short arm with the hook 9b inclined upwards. The start plate 8 is still latched at its left-hand position of Figure 4. The relationship of the lever 9 and the lateral projection 3a is as shown in Figure 8.

The means by which the trip plate 5 is lifted in response to either overload or voltage failure may be substantially the same as those described on my prior Patent No. 2,431,886 granted December 2, 1947. That is to say the windings 4 have dash pot controlled plungers 11 which are lifted by overload and thereby lift said trip plate 5 which overlies them, and also have no-volt armatures 12 which rise under spring bias under conditions of no-voltage and thereby, again, lift said trip plate 5 which overlies them.

In order that the trip plate 5 shall remain at the down position when the switch is not in use, a pivoted holding plate 13 is provided pivoted about the same axis 7 as the trip plate. This holding plate overlies the no-volt armatures 12 and is normally spring biased downwardly so as to hold said no-volt armatures down against their bias when the switch is not in use.

The means for latching the start plate 8 at its left-hand position consists of a stop-and-reset element 14 which pivots about a fixed axis 15 transverse to the plane of said start plate. This stop-and-reset element has two arms 14a, 14b projecting to the left one above the other and it is biased clockwise, i. e. the said arms are biased upwards. The start plate at its upper edge has a horizontally bent-over lug 8a which overlies the upper edge of the lower arm 14b of the stop-and-reset element 14 and thereby limits the clockwise movement of the latter. The upper arm of said stop-and-reset element is immediately underneath the holding plate 13. Said stop-and-reset

element also carries a leaf spring 16 projecting to the left above the holding plate.

When the start plate 8 is at its off or right-hand position, said bent-over lug 8a of said start plate retains said stop-and-reset element so far counter-clockwise that its upper arm is clear of the underside of said holding plate 13 and said spring 16 presses said holding plate to the down position. This is the position of Figure 3. When the start plate 8, in moving to the left, reaches the closed position of the switch said bent-over lug 8a reaches a downwardly stepped portion 14c of the lower arm of said stop-and-reset element 14, and consequently the latter is capable of rotating a given distance in the clockwise direction to the position of Figure 4. The start plate 8 is now latched by the step at 14c against return movement, and also the spring 16 has moved clear of the holding plate 13 and the upper arm 14a of said stop-and-reset element has moved far enough up to lift said holding plate clear of the no-volt armatures. Thus, the no-volt armatures 12 are free to lift the trip plate 5 and cause the same to exercise its tripping function and, at the same time, the start plate 8 is latched at its left hand position. It will be seen that if, in the interval subsequent to the closure of the switch contacts 1, 2 and prior to the release of the no-volt armatures 12, a heavy overload should occur, the overload plungers 11 will be free to rise and lift the trip plate, despite the fact that the no-volt armatures are still held down.

Assuming that the switch has been tripped by overload or phase failure as heretofore described, the starting plate 8 will be still latched at the position of Figure 4 and the correlation of the lever 9 and the projection 3a will be as in Figure 8. In order to reset the mechanism for enabling the switch to be again closed, said stop-and-reset element 14 is rotated counter-clockwise by hand. This moves the step 14c on the lower arm 14b of said stop-and-reset element clear of the bent-over lug 8a on the start plate 8, so that the latter can spring back to the right-hand position. At the same time the upper arm 14a of the stop-and-reset element 14 and also the spring 16 move down and the holding plate is again returned by the spring 16 to its down position, and, the bent-over lug 8a on the stop plate being now at the right-hand position, the stop-and-reset element 14 will be prevented from returning clockwise, so the holding plate will remain down.

The start plate 8, in returning to the right, carries the lever 9 with it. Said lever first moves with its orientation unchanged (i. e. with its long arm inclined to the left and its short arm inclined upwardly) until the hook portion 9b has passed over the lateral projection 3a on the contact-carrying bar 3. Just after this a downward tail projection 9c at the lower end of said lever to the left of the hook portion 9b engages said projection 3a and consequently said lever 9 is turned in a clockwise direction about its pivot point 10 until its long arm is upright or inclined a little to the right and the short arm is horizontal or inclined a little downwardly. During this movement the upper end of said long arm rides under the arm 6 of the trip plate 5, temporarily lifting said arm 6. The hook portion 9b moves down into position to the right of the projection 3a on the contact-carrying bar 3. The switch is thus now fully reset.

Assuming that the switch is closed, to open it voluntarily the stop-and-reset element 14 is moved by hand counterclockwise as before, and

this, as before, will permit the start plate 8 to spring back to the right hand position, and will cause the holding plate 13 to be pressed down by means of the spring 16. As this latter takes place before the switch contacts 1 and 2 open, there is no moment when the trip plate 5 is lifted. Consequently the upper end 9a of the long arm of the lever 9 remains to the right of the arm 6 of the trip plate, and the contact-carrying arm 3 simply moves to the right with the hook portion 9b of the lever. Thus the whole mechanism is set for re-closure by the start plate 8.

Describing now certain constructional details of the invention the fixed contacts 1 are mounted on a main body 17 of insulating material. The contacts 1 of the bottom row pass through to the front of the body 17 where they are fitted with connecting screws 18. The contacts 1 of the top row are electrically connected to terminals 19 at the back of said body 17. Other terminals 20 are mounted at the back of said body side by side with the contacts 1 of the bottom row. These terminals 20 pass through to the front of said body where they are fitted with connecting screws 21. The windings 4 are connected across the respective pairs of connecting screws 19 and 21 at the front of the body 17, by conductors 22 one of which is seen in Figure 5, and it will be seen that by connecting the respective pairs of terminals 19 and 20 at the back of said body in the three phases of the controlled circuit, circuit connections will be completed through the windings 4 when the bridging contacts 2 are moved to the bridging position in contact with the contacts 1.

The contact-carrying bar 3 is slidable in a guide groove in the back of the body 17. The biasing of said bar 3 to the open position of the contact 2 is effected by means of a coiled torsion spring 23 mounted in a recess in the front of said body 17 and having an extending arm 23a which engages the end of said bar 3, as shown in Figures 2, 3 and 4. As shown in Figure 2 the arm 23a hooks round the end of said bar 3, and thus serves to retain that end of said bar within its guide groove. For retaining the other end of said bar in its guide groove, the start plate, which slides against the front face of said body 17, has a rear tail extension 8b which passes round from the front to the back of said body where it overlaps said bar 3 as best shown in Figure 2.

The start plate 8 is guided in its sliding movement against the front face of the body 17 by means of locating studs 24 and 25 on said front face engaging in cut-outs 26 and 27 in said start plate, and also by the tail extension 8b engaging in a groove 28 in the front face of said body. Said start plate is retained against said front face of said body by means of a plate 29 secured against the front face of the body.

The plate 29 carries the three windings 4 together with the overload plungers 11, the no-volt armatures 12 and the dash pots 30 by which said overload plungers are controlled. The structure carried by said plate 29 is substantially as described in my Patent No. 2,431,886 aforesaid and forms, in itself, no part of the present invention. It is sufficient to say that the vertical plates 31 are rigidly mounted in front of the windings 4 and that the no-volt armatures 12 are pivoted on the upper edges of said plates 31 and have tail extensions 32 which are biased downwardly by means of tension springs 33 whose upper ends are connected to said tail extensions and whose lower ends are connected to points near the lower ends of said plates. Thus the no-volt armatures

themselves are biased upwardly, and move upwardly upon the occurrence of voltages failure. The overload plungers 11 are biased downwardly by gravity and are raised upon the occurrence of overload.

The pivot axis 7 of the trip plate 5 and the holding plate 13 is constituted by a length of wire carried by the body 17 as will be clear from the drawing. The arm 6 of said trip plate overlies the plunger 11 and no-volt armature 12 of the centre winding 4, and, in addition there are two other arms 34 and 35 which overlie the plungers 11 and no-volt armatures 12 of the other windings 4. Thus, as before stated, the trip plate 5 is lifted upon the rising of any of the overload plungers or any of the no-volt armatures.

A common horizontally arranged tension coil spring 36 serves both to bias the start plate 8 to its right hand position (according to Figures 3 and 4) and the stop-and-reset element 14 in the clockwise direction. This spring 36 at its left hand end is connected (as best shown in Figures 3 and 4) to the forward end of the start plate 8, and, at its right hand end to the bottom of the stop-and-reset element 14.

The lever 9 is guided in its travel by being mounted between the start plate 8 and the front face of the body 17. The stop-and-reset element is mounted on the body 17 as will be clear from the drawing. It consists of a plate bent in plan to U form, the arm 14a being on one side of the U and the arm 14b on the other.

In practice the whole mechanism may be enclosed in a casing (not shown) which has two push buttons mounted in one of its walls; viz. a start push button which, on depression, presses the start plate to the left by engaging the tail extension 8b, and a stop-and-reset push button which on depression engages the stop-and-reset element 14 and rotates it counter-clockwise.

I claim:

1. An electrical switch mechanism comprising an actuating element movable to an operative position and returnable to a non-operative position, a lever pivotably mounted between its ends on said actuating element, a switch element movable along a given path in one direction to a switch closing position and in the other direction to a switch opening position, means biasing said switch element to said switch-opening position, a tripping element having a normal position and a tripping position, means for maintaining said tripping element at said normal position in response to the electrical conditions in the circuit controlled by said switch being normal, and for moving said tripping element to said tripping position in response to said electrical conditions being abnormal, said tripping element, at its normal position, being located to engage and retain one end of said lever, upon said actuating element being moved from its inoperative to its operative position, whereby the other end of said lever is moved, and said other end being located to engage said switch element by such movement and convey it to the switch closing position, and said tripping element, upon moving to the tripping position, disengaging and releasing the first-named end of said lever, whereby said switch element is returned by said biasing means to said switch-opening position.
2. An electrical switch mechanism comprising an actuating element movable to an operative position and returnable to a non-operative position, a lever pivotably mounted between its ends on said actuating element, a switch element mount-

ed independently of said lever for movement along a given path in one direction to a switch closing position and in the other direction to a switch opening position, means biasing said switch element to said switch-opening position, a tripping element having a normal position and a tripping position, means for maintaining said tripping element at said normal position in response to the electrical conditions in the circuit controlled by said switch being normal, and for moving said tripping element to said tripping position in response to said electrical conditions being abnormal, said tripping element, at its normal position, being located to engage and retain one end of said lever, upon said actuating element being moved from its inoperative to its operative position, whereby the other end of said lever is moved, and said other end being located to engage said switch element by such movement and convey it to the switch closing position, and said tripping element, upon moving to the tripping position, disengaging and releasing the first-named end of said lever, whereby said switch element is released by said other end and returned by said biasing means to said switch-opening position.

3. An electrical switch mechanism comprising an actuating element movable to an operative position and returnable to a non-operative position, means biasing said actuating element to said non-operative position, a manually releasable latch for automatically latching said actuating element at said operative position, a lever pivotably mounted between its end on said actuating element, a switch element movable along a given path in one direction to a switch closing position and in the other direction to a switch opening position, means biasing said switch element to said switch-opening position, a tripping element having a normal position and a tripping position, means for maintaining said tripping element at said normal position in response to the electrical conditions in the circuit controlled by said switch being normal, and for moving said tripping element to said tripping position in response to said electrical conditions being abnormal, said tripping element, at its normal position, being located to engage and retain one end of said lever, upon said actuating element being moved from its inoperative to its operative position, whereby the other end of said lever is moved, and said other end being located to engage said switch element by such movement and convey it to the switch closing position, and said tripping element, upon moving to the tripping position, disengaging and releasing the first-named end of said lever, whereby said switch element is returned by said biasing means to the switch-opening position.

4. An electrical switch mechanism comprising an actuating element movable to an operative position and returnable to a non-operative position, means biasing said actuating element to said non-operative position, a manually releasable latch for automatically latching said actuating element at said operative position, a lever pivotably mounted between its ends on said actuating element, a switch element movable along a given path in one direction to a switch closing position and in the other direction to a switch opening position, means biasing said switch element to said switch-opening position, a tripping element having a normal position and a tripping position, means for maintaining said tripping element at said normal position in response to the electrical conditions in the circuit controlled by said switch

being normal, and for moving said tripping element to said tripping position in response to said electrical conditions being abnormal, said tripping element, at its normal position, being located to engage and retain one end of said lever, upon said actuating element being moved from its inoperative to its operative position, whereby the other end of said lever is moved, and said other end being located to engage said switch element by such movement and convey it to the switch closing position, and said tripping element, upon moving to the tripping position, disengaging and releasing the first-named end of said lever, whereby said switch element is returned by said biasing means to the switch-opening position, and means whereby, upon said actuating element, subsequently to the return of said switch element to the switch opening position in response to abnormal circuit conditions, returning to the non-operative position under its spring bias in response to the release of said latch, said other end of said lever engages said switch element, whereby said lever is returned to the position for its first-named end to engage said tripping element upon said actuating element being again moved to the operative position.

5. An electrical switch mechanism comprising an actuating element movable to an operative position and returnable to a non-operative position, means biasing said actuating element to said non-operative position, a manually releasable latch for automatically latching said actuating element at said operative position, a lever pivotably mounted between its ends on said actuating element, a switch element movable along a given path in one direction to a switch-closing position and in the other direction to a switch-opening position, means biasing said switch element to said switch-opening position, a tripping element having a normal position and a tripping position, means for maintaining said tripping element at said normal position in response to the electrical conditions in the circuit controlled by the switch being normal, and for moving said tripping element to said tripping position in response to said electrical conditions being abnormal, said tripping element, at its normal position, being located to engage and retain one end of said lever upon said actuating element being moved from its inoperative to its operative position, whereby the other end of said lever is moved, first and second projections formed on said other end of said lever, said first projection being located to engage said switch element, by such movement of said other end of said lever, and convey said switch element to the switch closing position, and said tripping element, upon moving to the tripping position, disengaging and releasing the first-named end of said lever, whereby said switch element is released by said first projection and is returned by its biasing means to said switch-opening position, and means whereby, upon said actuating element, subsequently to the return of said switch element to the switch opening position in response to abnormal circuit conditions, returning to the non-operative position under its spring bias in response to the release of said latch, said second projection engages said switch element, whereby said lever is returned to the position for its first-named end to engage said tripping element upon said actuating element being again moved to the operative position.

6. An electrical switch mechanism comprising an actuating element movable to an operative

position and returnable to a non-operative position, means biasing said actuating element to said non-operative position, a manually releasable latch for automatically latching said actuating element at said operative position, a lever pivotably mounted between its ends on said actuating element, a switch element movable along a given path in one direction to a switch closing position and in the other direction to a switch opening position, means biasing said switch element to said switch opening position, a tripping element having a normal position and a tripping position, means for maintaining said tripping element at said normal position in response to the electrical conditions in the circuit controlled by said switch being normal, means for moving said tripping element to said tripping position in response to no-volt conditions in said circuit, means controlled by said latch for preventing such movement of said tripping element in response to such no-volt conditions when said latch is at its normal non-latching position and for permitting such movement when said latch is latching said actuating element at its operative position, said tripping element, at its normal position, being located to engage and retain one end of said lever, upon said actuating element being moved from its inoperative to its operative position, whereby the other end of said lever is moved, and said other end being located to engage said switch element by such movement and convey it to the switch closing position, and said tripping element, upon moving to the tripping position, disengaging and releasing the first-named end of said lever, whereby said switch element is released by said other end and returned by its biasing means to said switch opening position.

7. An electric switch mechanism comprising an actuating element movable to an operative position and returnable to a non-operative position, means biasing said actuating element to said non-operative position, a manually releasable latch for automatically latching said actuating element at said operative position, a switch element movable along a given path in one direction to a switch closing position and in the other direction to a switch opening position, means biasing said switch element to said switch opening position, transmission means whereby movement of said actuating element to said operative position effects movement of said switch element to said switch closing position, a no-volt armature, a winding for said no-volt armature in the circuit controlled by said switch, said winding when energised maintaining said armature at an attracted position, means biasing said no-volt armature to the non-attracted position, means for tripping said transmission means in response to movement of said no-volt armature to the non-attracted position, and thereby permitting said switch element to return to the switch-opening position, and means controlled by said latch for preventing movement of said no-volt armature to the non-attracted position when said latch is at its normal non-latching position and for permitting such movement when said latch is latching said actuating element at said operative position.

8. An electric switch mechanism comprising an actuating element movable to an operative position and returnable to a non-operative position, means biasing said actuating element to said non-operative position, a manually releasable latch for automatically latching said actuating element at said operative position, a switch element movable along a given path in one direction

to a switch closing position and in the other direction to a switch opening position, means biasing said switch element to said switch opening position, transmission means whereby movement of said actuating element to said operative position effects movement of said switch element to said switch closing position, a winding in the circuit controlled by said switch, a no-volt armature for said winding having an attracted and a non-attracted position and biased to its non-attracted position, an overload armature for said winding having an attracted and a non-attracted position and biased to its non-attracted position, said winding when normally energised maintaining said no-volt armature at its attracted position and leaving said overload armature at its non-attracted position, and, when energised by overload, moving said overload armature to the attracted position, means for tripping said transmission means in response to movement of said no-volt armature to the non-attracted position or movement of said overload armature to the attracted position, and thereby permitting said switch element to return to the switch opening position, and means controlled by said latch for preventing movement of said no-volt armature to the non-attracted position when said latch is at its normal non-latching position, and for permitting such movement when said latch is latching said actuating element at its latching position, said last-named means in no circumstances preventing movement of said overload armature to its attracted position.

9. An electric switch mechanism comprising an actuating element movable to an operative position and returnable to a non-operative position, means biasing said actuating element to said non-operative position, a manually releasable latch for automatically latching said actuating element at said operative position, a switch element movable along a given path in one direction to a switch closing position and in the other direction to a switch opening position, means biasing said switch element to said switch opening position, transmission means whereby movement of said actuating element to said operative position effects movement of said switch element to said switch closing position, a winding in the circuit controlled by said switch, a no-volt armature for said winding having an attracted and a non-attracted position and biased to its non-attracted position, an overload armature for said winding having an attracted and a non-attracted position and biased to its non-attracted position, said winding when normally energised maintaining said no-volt armature at its attracted position and leaving said overload armature at its non-attracted position, and, when energised by overload, moving said overload armature to the attracted position, a tripping element having a normal position and a tripping position, said tripping element, when at its tripping position tripping said transmission means and thereby permitting said switch element to return to the switch opening position, means whereby movement of said no-volt armature to the non-attracted position or movement of said overload armature to the attracted position, effects movement of said tripping element to the tripping position and means controlled by said latch for preventing movement of said no-volt armature to the non-attracted position when said latch is at its normal non-latching position, and for permitting such movement when said latch is latching said actuating element at its latching position,

said last-named means in no circumstances preventing movement of said overload armature to its attracted position.

10. An electrical switch mechanism comprising a switch element movable in one direction to a switch-closing position and in the other direction to a switch-opening position, means biasing said switch element to said switch opening position, an actuating element movable to an operative position and returnable to a non-operative position, transmission means whereby movement of said actuating element to said operative position effects movement of said switch element to said switch closing position, a winding in the circuit controlled by said switch, a no-volt armature for said winding having an attracted and a non-attracted position and biased to its non-attracted position, an overload armature for said winding having an attracted and a non-attracted position and biased to its non-attracted position, said winding when normally energised maintaining said no-volt armature at its attracted position and leaving said overload armature at its non-attracted position, and when energised by overload, moving said overload armature to the attracted position, a tripping element having a position for tripping said transmission means, said tripping element being actuated to the tripping position by movement of said no-volt armature to the non-attracted position or movement of said overload armature to the attracted position and thereby permitting said switch element to return to the switch-opening position, a separate holding element, and an interlock between said actuating element and said holding element whereby said holding element engages said no-volt armature and holds it at the attracted position for all positions of said actuating element except said operative position and releases said no-volt armature at said operative position of said actuating element, said holding element at no time obstructing movement of said overload armature to its attracted position.

11. An electric switch mechanism comprising an actuating element movable to an operative position and returnable to a non-operative position, means biasing said actuating element to said non-operative position, a manually releasable latch for automatically latching said actuating element at said operative position, a switch element movable along a given path in one direction to a switch closing position and in the other direction to a switch opening position, means biasing said switch element to said switch opening position, transmission means whereby movement of said actuating element to said operative position effects movement of said switch element to said switch closing position, a winding in the circuit controlled by the switch, a no-volt plate armature at one end of said winding biased to a non-attracted position away from said winding, an overload plunger armature within said winding biased to a non-attracted position in the opposite direction to said

no-volt plate armature, said winding, when normally energised maintaining said no-volt armature in opposition to its bias at an attracted position and leaving said overload plunger armature at its non-attracted position, and when energised by overload moving said overload plunger armature through an opening in said no-volt plate armature to an attracted position, a tripping element having a normal position and a tripping position, said tripping element, when at its tripping position tripping said transmission means and thereby permitting said switch element to return to the switch opening position, means whereby, either said no-volt plate armature in moving to the non-attracted position or said overload plunger armature in moving to the attracted position engages said tripping element and moves it to the tripping position, and means controlled by said latch for preventing movement of said no-volt armature to the non-attracted position, when said latch is at its normal non-latching position, and for permitting such movement when said latch is latching said actuating element at its latching position, said last-named means in no circumstances preventing movement of said overload armature to its attracted position.

12. An electrical switch mechanism as claimed in claim 10, comprising a pivoted element constituting said interlock, said pivoted element having a first position at which it holds said holding element at the position for holding said no-volt armature at the attracted position, and a second position at which it releases said holding element, and means biasing said pivoted element to said second position, said actuating element engaging said pivoted element to hold the same at said first position at all positions of said actuating element except said operative position and to permit said pivoted element to move under said bias to said second position at said operative position of said actuating element.

13. An electrical switch mechanism as claimed in claim 12, wherein said actuating element is formed with a shoulder and said pivoted element in moving to said second position engages said shoulder to obstruct return of said actuating element to its non-operative position.
